US00D780492S

(12) **United States Design Patent** (10) **Patent No.:** **US D780,492 S**
Terada (45) **Date of Patent:** **** Mar. 7, 2017**

(54) **TABLE**

(71) Applicants: **ITOKI CORPORATION**, Osaka-shi, Osaka (JP); **Inter Office Ltd.**, Tokyo (JP)

(72) Inventor: **Naoki Terada**, Tokyo (JP)

(73) Assignees: **ITOKI CORPORATION**, Osaka-shi, Osaka (JP); **INTER OFFICE LTD.**, Tokyo (JP)

(**) Term: **15 Years**

(21) Appl. No.: **29/547,061**

(22) Filed: **Dec. 1, 2015**

(30) **Foreign Application Priority Data**

Jun. 2, 2015 (JP) 2015-012216

(51) **LOC (10) Cl.** **06-04**

(52) **U.S. Cl.**

USPC **D6/692**; D6/692.4; D6/349

(58) **Field of Classification Search**

USPC D6/334, 335, 349, 692, 692.4, 707.6;

297/16.142

CPC .. A47B 7/00; A47B 11/00; A47C 1/00; A47C
